UNITED STATES PATENT OFFICE.

HENRY C. HERR, OF PITTSBURGH, PENNSYLVANIA, ASSIGNOR TO FIBER BARREL MACHINERY & MANUFACTURING COMPANY, OF PITTSBURGH, PENNSYLVANIA, A CORPORATION OF PENNSYLVANIA.

MACHINE FOR APPLYING CHINE-HOOPS TO CYLINDRICAL BODIES.

1,265,712.

Specification of Letters Patent.

Patented May 7, 1918.

Application filed October 30, 1913. Serial No. 798,356.

To all whom it may concern:

Be it known that I, HENRY C. HERR, a citizen of the United States of America, residing at Pittsburgh, in the county of Allegheny and State of Pennsylvania, have invented certain new and useful Improvements in Machines for Applying Chine-Hoops to Cylindrical Bodies, of which the following is a specification, reference being had therein to the accompanying drawings.

The invention relates to the manufacture of barrels and similar packages, and has more particular reference to mechanism for applying chine-hoops thereto. As specifically shown, the machine is adapted for the application of such hoops to cylindrical bodies formed of paper or fibrous material, and it is the object of the invention to apply a hoop that will reinforce and strengthen the chine and also will bind the edge and form an inner seat for the reception of the head.

The invention comprises, first, means for positioning the hoops upon the chine; further, means for contracting and tightening said hoops upon the body; and further, various features of construction as hereinafter set forth.

In the drawings:

Figure 1 is a side elevation of the machine;

Figs. 2 and 3 are elevations at opposite ends of the machine;

Fig. 4 is a cross section showing in elevation the hoop-contracting mechanism;

Fig. 5 is a longitudinal section on line $x-x$ Fig. 4;

Fig. 6 is a central section through one of the eccentric bushings;

Fig. 7 is a sectional view of the hoop and the body to which the hoop is to be secured before the machine has operated;

Fig. 8 is a sectional view of the hoop and the body to which the hoop is secured after the machine has operated.

1 is a suitable bed or frame upon opposite ends of which are vertical extensions 2 and 3 carrying the hoop-applying mechanism for opposite ends of the barrel, sufficient clearance being provided between these extensions for receiving the barrel body.

These mechanisms at opposite ends of the machine are in many respects exact duplicates, but provision is made for a relative movement longitudinally of the bed, which necessitates the mounting of one of the mechanisms on a traveling head, whereas the other may remain in fixed position. Each of these duplicate mechanisms comprises a head 4, which has a portion adapted to fit within the end of the cylindrical body, and an annular shoulder portion 5 for bearing against the end of the chine-hoop and pressing it into full engagement with the body. The heads 4 are mounted upon rotary shafts 6 and 6^a, which, in the operation of the machine, are revolved in unison through the medium of mechanism of the following construction:

7 is a shaft extending longitudinally and centrally of the bed 1 and journaled in suitable bearings therein. 8 and 9 are gear-wheels upon opposite end portions of this shaft, and which respectively engage pinions 10 and 11 upon the shafts 6 and 6^a. As these intermeshing gear-wheels and pinions are in the same ratio, it is obvious that the shafts 6 and 6^a will revolve in unison.

Adjacent to each of the heads 4 is a non-revolvble head 12, upon which is mounted a series of rock-arms 13 provided at their free ends with rollers 14 arranged opposite the periphery of the head 4. Each rock-arm 13 is connected by a pin 15 with a ring-member 16 engaging a grooved bearing in the head 12, which is concentric with the axis of the shaft 6. The pins 15 engage radial slotted bearings 17 in each of the rock-arms 13, and the construction is therefore such that a rotary adjustment of the ring 16 will impart a simultaneous and equal rocking movement to all of the arms 13, which will cause the rollers 14 to move toward or from the periphery of the rotary heads 4. In addition to the rock-arms 13 there is provided a rock-arm 18, which carries a roll 19 having perforating punches 20 in the periphery thereof. This rock-arm 18 is mounted on a rock-shaft 21 journaled in the head 12, at the opposite end of which is a rock-arm 22 having at its free end a roll 23 engaging a cam groove in a gear-wheel 24,

which is driven from a pinion 25 upon the shaft 6. The wheel 24 is also provided with a second cam, preferably on the opposite side thereof, which engages a rock-arm 26 connected with a gear-segment 27 which engages a gear-segment 28 in the periphery of the ring 16. Thus during the rotation of the shaft 6 and head 4, movement is communicated to the cam wheel 24 by the pinion 25, which causes the rocking of the arms 13 and 18, as will be more fully herein-after described. The rock-arms 13 and 18 are normally under tension of springs 13^a and 18^a, which springs are anchored upon the head 12 and tend to move said arms toward adjustable stops 13^b and 18^b.

As thus far described, the mechanisms upon opposite ends of the machine are duplicates, but, as previously stated, one of these mechanisms is mounted upon a slide 29 movable longitudinally of the bed. As shown in Fig. 1, the mechanism on the left-hand end is mounted upon a slide 29 engaging suitable slideways in the outward extension 2 of the frame. This slide is actuated by a cam 30, preferably formed integral with the gear-wheel 8, and which engages a roll 31 connected with the slide. A yielding connection is preferably provided between the roll and the slide, comprising a sliding block 32 to which the roll is directly attached, which block is recessed to receive a spring 33 engaging a bearing 34 at the end of the shaft 6. The sliding block 32 has an aperture therein through which the reduced end of shaft 6 reciprocates. A set-screw 35, secured to the vertical extension 2, bearing against the opposite end of the block 32 serves to adjustably limit the movement.

The construction just described is such that the rotation of the cam 30 will impart a reciprocatory movement to the slide 29, and as all of the mechanism surrounding the head 4 is mounted upon this slide, it will move as a unit along the bed 1. This movement does not interfere with the transmission of rotary movement to the shaft 6, as the pinion 10 is of sufficient length to remain in mesh with the gear-wheel 8 during this movement. The gear-wheel 8 is driven from a suitable drive pulley 36 sleeved upon the end of the shaft 7 and turning freely thereon, through the medium of an intermediate transmission, including a pinion 37 connected with the pulley 36, a clutch-wheel 38 driven from said pinion, a shaft 39 driven from the clutch-wheel, and a pinion 40 on said shaft meshing with the gear-wheel 8. The clutch-wheel 38 contains a suitable trip-mechanism 38' of any well known type (not shown in detail) which is controlled by a hand-lever 41, and which is adapted upon the actuation of said lever to communicate motion from the wheel

38 to the shaft 39, and continue it through one complete revolution, after which further movement is arrested.

For engaging and disengaging the cylindrical body upon the bed or frame, there are mounted upon the bed 1 inclined cross-tracks 42 and adjacent to these tracks are rock-arms 43 connected by an intermediate lever system with a controlling lever 44. These rock-arms 43 act as stops in certain positions, they being so arranged that in connection with the inclined tracks 42 they will normally serve to support a cylindrical barrel body upon the bed, in substantially axial alignment with the heads 4; but upon a movement of the lever 44 the rock-arms are depressed to release said body and permit it to roll off of the inclined tracks.

In the operation of the machine the cylindrical bodies to which the chine-hoops are to be applied, are successively fed upon the inclined tracks 42 and will automatically assume a position in substantial alignment with the heads 4. The lever 41 is then operated to trip the clutch mechanism and communicate motion from the drive pulley 36 to the shaft 39, and through the pinion 40 to the gear-wheel 8. This gear-wheel being in mesh with the pinion 10 will drive the latter, while an exactly corresponding movement is transmitted to the pinion 11 through the shaft 7 and gear-wheel 9. Before being fed upon the machine, the barrel body has the chine hoops for the opposite ends thereof loosely placed in position. These hoops will therefore be concentrically arranged in relation to the heads 4 and when the head on the left-hand end of the machine, Fig. 1, is moved toward the opposite head said hoops will mount up on the heads 4, the inner ends of which are tapered. This movement of the left-hand head is effected, as above described, by the cam 30 imparting movement to the roll 31 on the slide 32, and through the yielding spring 33 transmitting movement to the slide 29. The amount of movement is sufficient to completely force the hoops upon the ends of the body, and any slight variation in the length of said bodies will be taken care of by the yielding of the spring 33.

After the hoops are thus fully engaged with the cylindrical body, the further rotary movement of the heads 4 and the corresponding movement of the cams 23 and 24 will cause a rocking of the arms 22 and 26. The latter will actuate the gear-segment 27, which is in mesh with the gear-segment 28 on the ring 16, imparting a rotary movement to the latter, which, through the engagement of the pins 15 with the slide bearings 17 in the rock-arms 13, will cause a simultaneous and equal rocking movement of all of said arms. This will carry the rolls 14 inward causing them to bear against the

chine-hoop and rolling the outer part of same so as to cause a contraction in diameter and a forcing inward into firm contact with the cylindrical body. The rock-arm 22 will cause the inward rocking of the arm 18, which carries the punch wheel 19, and the latter during the rotation of the head 4 will form a row of perforations or indentations in the chine-hoop which will assist in contracting the same and in securing it to the body. The inward movement of the rolls 14 and 19 is assisted by the springs 13^a and 18^a, while the stops 12^b and 18^b will limit the inward movement. The timing is such that only one complete revolution of the head is performed while the punch roll 19 is in operation.

At the completion of the operation above described the chine-hoops on both ends of the barrel will have been rolled and contracted in diameter to firmly attach the same to the barrel body. The cam 30 has not, however, completed its movement and during the remaining portion of the cycle will operate to withdraw the slide 29, separating the heads 4 and withdrawing the same from engagement with the chine-hoops and the cylindrical body to which they have been applied. This permits the barrel to rest upon the inclined tracks 42 and rock-arms 43, but when the operator actuates the lever 44, the rock-arms 43 will be withdrawn permitting the barrel to roll off from the inclined tracks.

In applying hoops to bodies formed of different gages of stock their outside diameter must be varied. This requires an adjustment in the hoop-contracting mechanism which I have provided for as follows: The rock-arms 13 are pivoted upon studs 45, which, as shown in Fig. 6, engage eccentric bushings 46 in the head 12. These bushings are provided with gear-teeth engaging adjustable screws 47 in the head 12, operable from the periphery thereof. This permits of rotating the eccentric bushing so as to move the studs 45 inward or outward, which will compensate for variations in thickness of the stock. When adjusted the studs 45 are clamped in position by nuts 48 engaging threaded portions 49 thereof.

To protect the mechanism surrounding the heads an annular shield 50 is preferably placed thereabout, as shown.

What I claim as my invention is:

1. The combination with a bed, of duplicate mechanisms mounted upon opposite ends of said bed, each comprising a standard, a rotary horizontally-arranged shaft, a head mounted on said shaft, a series of rolls surrounding said head, mechanism for moving said rolls correspondingly inward and outward, and a cam controlling said mechanism driven in timed relation to said rotary shaft; a carriage on which one of said duplicate mechanisms is mounted movable longitudinally of said bed, mechanism for correspondingly driving said duplicate mechanisms, permitting of the movement of said carriage, and means for moving said carriage timed with the movement of said duplicate mechanisms to cause a sequence of operations; substantially as shown and for the purpose described. 70
2. The combination with a bed, of duplicate mechanisms mounted upon opposite ends of said bed for engaging and rolling chine-hoops upon opposite ends of a cylindrical body, inclined cross-tracks on said bed, a stop for arresting a cylindrical body on said inclined cross-tracks in axial alignment with said duplicate mechanisms to retain the same during the operation of the engaging and rolling of the hoops upon the body, and means for withdrawing said stop to permit the hooped barrel to roll off said inclined cross-tracks at the completion of the operation. 75
3. The combination with means for pressing a hoop in engagement with a cylindrical body, of a relatively-movable member, a series of rolls mounted upon said member surrounding the periphery of said hoop, a separate punching roll adapted to contact with the periphery of said hoop, means adapted to actuate said series of rolls into contact with the periphery of said hoop, and means adapted to actuate said separate punching roll into contact with the periphery of said hoop, both of said last-mentioned means including a cam member common to both. 80
4. The combination with an annular member for bearing against the end of a hoop, of a concentrically-arranged, relatively-movable member, eccentric serrated bushings in said last-mentioned member, studs engaging said bushings, rock-arms pivoted upon said studs, rollers attached to said rock arms and adjustable screws engaging the serrations of said bushings, whereby the positions of the rolls relative to said annular member may be adjusted to compensate for variations in thickness of the stock of the body to which the hoop is applied. 85
5. The combination with a revoluble member adapted for engagement with a cylindrical body having a hoop thereon, of a stationary member having a grooved bearing, rolls pivoted upon said stationary member, arranged adjacent to the periphery of said hoop, and a ring member engaging said grooved bearing in the stationary member, movable relative thereto and pivotally connected to said rolls. 90
6. The combination with a member adapted for engagement with a cylindrical body having a hoop thereon, of a relatively movable member, a series of rolls mounted upon said relatively movable member and surrounding the periphery of said hoop, a separate punching roll mounted upon said 125

relatively movable member, adapted to contact with the periphery of said hoop, a ring member having a portion of its periphery toothed, said member being rotatably mounted upon said relatively movable member; a toothed segment, for engaging said toothed peripheral portion, and separate rock arms connected to said toothed segment and

10
In testimony whereof I affix my signature in presence of two witnesses.
